UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE

TYPEWRITING MACHINE

Application filed March 9, 1927. Serial No. 173,821.

This invention relates to a tally-strip mechanism, which may be used in connection with a fan-fold typewriting machine, such for instance as the one disclosed in the patent to

5 Wernery & Smith, No. 1,132,055.

In said machines a multiple-ply web is usually drawn from a supply at the rear of the machine and is interleaved with carbons to form a pack which is inserted around the platen to be typed upon. After typing a form the platen is elevated to straighten out the web and to gage the forms to length, after which the carbons are stripped to a new form: then the platen is lowered to its normal position and the typed forms are torn off against a knife.

Sometimes it is desired to use alternately a plurality of webs on the same machine, and it is customary to provide the machine with 20 webs each having its own carbon-carrier so as to facilitate the web-changing operation. These additional carbon-carriers render unnecessary the usual rethreading of the web with carbons each time that the web is replaced. The usual condensed record-sheet 25 for receiving the items typed on all the webs cannot be used with this type of machine, because the record-sheet usually overlies the uppermost ply of the active web and renders it difficult to replace the webs without first withdrawing the record-sheet.

It is one of the features of this invention to provide a record-sheet adapted to alternately receive a copy of all the items entered 30 on either web without removing the record-sheet which is at all times held in registration around the platen.

This invention can also be used to advantage for many classes of work in which a multiple-ply web is used in connection with a tally-strip, although the nature of the tally-mechanism is such that the machine may be used for regular fan-fold work without the tally-strip when desired. This feature is important as it does not impair the usefulness of the machine for regular work. In the present invention, the record or tally strip is supplied to the machine from a roll or spool which is mounted on plates carried by the platen-frame. The tally-strip is drawn down-

wardly from said spool and is passed around the platen, and is then rewound onto a receiving spool, which is provided with a finger-wheel and a retaining ratchet to prevent accidental unwinding thereof. This strip is the innermost ply, that is, nearest the platen, the web being placed over the strip. The web is positioned for the first line of typing by elevating the platen and pulling the web forwardly. Then, after the platen is lowered to its normal position, the web and the tally-strip are both line-spaced together, but since the tally-strip-receiving spool is not automatically rotated when rotating the platen, a loop is formed between the platen and the receiving spool. After typing a form, and prior to elevating the platen to shift the carbons, the tally-strip-receiving spool is wound up by hand to take up the slack of the strip, and the supply spool is locked against rotation so that the tally-strip may be held tight around the platen while displacing the carbons. Sometimes, the web is provided upon the rear carriage with an extra carbon overlying the upper ply thereof, and, in this instance, the carbon has the carbonized side thereof contacting with the tally-strip to thereby transfer the matter typed on the web to the tally. This extra carbon is shifted together with the other carbons. In certain classes of work, however, it is sometimes desired to use a carbon together with the tally-strip, both being drawn together from the same supply spool and being rewound together on the receiving spool.

In one form of the invention the supply spool may be locked against rotation automatically by means of linkage, which is operatively connected to the platen-frame-locking latch. In this form of the invention, when the latch is swung backwardly to release the platen-frame, a pawl is forced into the path of the teeth of a ratchet carried by the supply spool, thereby preventing its rotation during the time the platen is elevated.

The tally-strip mechanism, which is attached to the platen-frame of the machine, is slanted to the rear of the machine so as to follow the usual inclination of the front paper-table, which facilitates reading of the

typed forms. This, of course, renders the platen top-heavy and it is difficult to shift it to upper-case position. In order to improve this condition, there are provided a pair of side links which keep the platen straight during a shifting movement. The use of this means for guiding the platen-frame is, however, not restricted to this tally-mechanism, but it may be used to advantage to steady a platen-frame designed to carry other heavy attachments, such as collating tables of many kinds, stencil-cutting devices, etc.

Other features and advantages will herein-after appear.

15 In the accompanying drawings,

Figure 1 is a perspective view showing the invention applied to an Underwood continuous billing typewriting machine having a displaceable and shiftable platen.

20 Figure 2 is a detail, showing the means for frictionally holding the supply spool on its driving shaft.

Figure 3 is a cross-sectional view, in elevation, showing the web and the tally-strip 25 after typing a form.

25 Figure 4 is a diagrammatic view, showing the tally-receiving roll in its locked position prior to displacing the platen.

Figure 5 is a diagrammatic view, showing 30 the platen in its displaced position, the carbons being shown shifted to a fresh form.

Figure 6 is a front view, partly in cross-section, showing some of the constructional features of the tally supply and receiving 35 spools.

Figure 7 illustrates a form of the invention in which a carbon is wound together with the tally-strip onto the receiving spool. This carbon takes the place of the upper carbon 40 shown in Figure 1.

Figure 8 is a side view, in elevation, showing the novel mechanism for insuring a straight movement of the platen in its case-shifting movement.

45 Figure 9 is a diagrammatic view, showing one form of the invention in which the means for locking the receiving spool prior to swinging the platen is operatively connected to the platen-locking latch.

50 This invention is preferably applied to an Underwood continuous billing typewriting machine which has a platen 10 rotatably mounted by means of a shaft 11 on a displaceable platen-frame 12. This machine is used for handling a multiple-ply web 13, the plies of which are interleaved with carbons 14 fast to a carbon-carrier 15 arranged to reciprocate on a carbon-carrier frame 16 to re-position the carbons at intervals to untyped 55 portions of the web. The assembled web is inserted at the rear of the platen over a rear table 17, and is positioned around the platen to the printing point, in which position it is typed upon by means of type-bars 18, and 60 line-spaced upward over front table 110 as

the typing proceeds. After typing a form, the platen is elevated by swinging the platen-frame on a shaft 19 carried by a carriage 20, and after elevating the platen, the typed forms are gaged to length against the gage 21. While holding the web in this gaged position, as shown in Figure 5, the carbon-carrier 15 is moved away from the platen by means of a handle 22 to thereby present the carbons to the next form.

Sometimes it is desired to use several webs in connection with the same machine, and, in order to eliminate the necessity of threading the plies of the webs with carbons prior to inserting the web in the machine, it is customary to use a carbon-carrier having two sets of carbons, one set for each web, such as is illustrated in my pending application No. 108,451, filed May 12, 1926 (now Patent No. 1,690,844, dated November 6, 1928). 75

In this invention it is desired to make a condensed record of all the items typed on either of two webs, as shown in Figure 7. To this end, a record-sheet 23, having an associated carbon 24, Figure 7, is supplied to the machine in the form of a spool or roll 25 which is rotatably mounted by means of a cross-shaft 26 on side plates 27 and 28. These plates form an extension of the platen-frame 12 and are displaceable therewith. The record-sheet is drawn from the supply spool 25 and is passed over a cross-bar 29 and around the platen, from which it is rewound onto a receiving spool 30 also rotatably mounted on the plates 27 and 28 by means of a cross-shaft 31. The record-sheet is always ready to receive typing thereon, and also ready to be line-spaced together with the web by means of co-operating feed-rolls 32 and 33. One advantage of this arrangement is that 95 the displacement of the platen-frame does not 100 disturb the position of the record-sheet relatively to the printing line.

When line-spacing the record-sheet together with the web around the platen, a loop 110 is formed at the delivery side of the platen, which loop is taken up manually by winding the receiving spool which is provided with a finger-piece 34 at one end thereof. In order to prevent accidental unwinding of the 115 receiving spool, there is provided a ratchet-wheel 35 which is fast to the shaft 31 and co-operates with a retaining pawl 36 pivotally mounted on a stud 37 fast to the plate 28. This pawl is held in engagement with 120 the ratchet by means of a spring 38 which is wound around the stud.

In order to prevent shifting of the record-sheet around the platen when displacing the same, due to having tensioned the record-sheet when taking up the slack at the delivery side of the platen, it is proposed to lock the supply-spool against rotation just prior to displacing the platen. This may be done either manually, as shown in one form of the 130

invention, or automatically, as shown in another form of the invention. The manual means for locking said supply-spool is shown in Figure 1 and consists of a sliding member 39, operated by a finger-piece 40. Said member is slidably mounted on the side plate 27 by means of clips 40a and is moved in the path of teeth 41 of a ratchet-wheel 42 carried by the shaft 26, to thereby prevent rotation of the wheel. The sliding member 39 is normally held in its ineffective position by means of a spring 43, which is fast to the plate by means of rivets 44 and engages a notch 45 in said member. This ineffective position of said member is shown in Figure 1, and the operated position thereof is shown in Figure 4. The sliding member is held in its operated position by the same spring 43 which engages a notch 46.

In order to understand the automatic operation of the locking means for the supply-spool, it should be first noted that the platen-frame is held in its normal position, as shown, for instance, in Figure 4, by means of a locking latch 47 which is pivotally mounted on a cross-bar 48 and engages a locking pin 49 carried by the platen-frame. This latch is swung rearwardly away from the pin 49 in order that the platen may be elevated. In this form of the invention, advantage is taken of this movement of the latch 47 to simultaneously lock the supply-spool against rotation. Referring more particularly to Figure 9, in which the latch 47 is shown in its normal position, it will be noted that a forward extension 50 of the latch 47 engages a roller 51 which protrudes through a slot 52 in the side plate 28 and is carried by a link 53 which is operatively connected to a locking pawl 54 pivotally mounted on a pin 55 also carried by the plate 28. By means of said link, the latch 47 holds the pawl 54 in its ineffective position against the tension of a light spring 56, that is, a spring which is lighter than a spring 57 which operates the latch 47. Although the locked position of the pawl 54 is not shown in the drawings, it may be easily understood by reference to Figure 9, since it is evident that when the latch 47 is swung rearwardly and the roller 51 is released, the spring 56 will automatically throw the pawl 54 into engagement with the wheel 42, thereby preventing rotation thereof. This locked position will be maintained during the time that the platen is elevated and the pawl 54 will be automatically released as soon as the platen is swung back to its normal position.

In order to save carbon sometimes, especially when using only one web, the tally-strip is supplied to the machine without any carbon, and, in order to get a copy on the strip of the items typed upon the web, it is proposed to use an extra carbon 58 which overlies the web and has the carbonized side

thereof facing the tally-strip. This carbon is carried by the same carbon-holder and is displaced together with the other carbons. This arrangement saves carbon, since the same sheet may be used over and over until completely worn out.

The tally-strip is wound around a tube 60 carried by means of collars 61 and 62 by the shaft 31, by inserting the leading edge thereof in a slot 59 extending from one end to the other of the tube. Thus the leading edge is gripped on the tube to thereby drive the tally-strip therearound, the tube serving as a receiving or take-up spool. It is, of course, understood that rolls without flanges come under the expression spool. In order that the tally-strip may be easily taken off from the receiving spool, the pawl 36, which normally prevents unwinding of the spool, may be released by means of a finger-piece 63, which, by means of a stud 64, operates a cam-plate 65 engaging the inner face of the pawl 36, thereby swinging it away from the ratchet-wheel 35.

The replacement of the supply spool is facilitated by means of this invention. The shaft 26 is held in place on the plates 27 and 28 by means of flat spring 66 which is slidably mounted on a pair of studs 67 carried by the plate 28, the heads of the studs retaining the spring. The end of the spring is slotted at 68 to straddle the shaft 26 in a slot 69 at the end thereof. In order to remove the spool, the spring 66, which is provided with a finger-piece extension 70, is moved downwardly away from the shaft and then the shaft is bodily removed from its supporting bearings. The supply-spool proper, that is, the part which is replaced consists of a card-board tube 71 which is supported by means of end flanges 72 and 73. The flanges are provided with flexible jaws 74 fitting into the tube 71 to thereby laterally confine the tally-strip. The flange 72 has a hole therein for receiving a pin 75 carried by a collar 76 fast to the shaft 26 by means of a screw 77. In order that the flange 72 may be held in continuous contact with the collar 76 to thereby rotate therewith, there is provided a spring 78, such as shown in Figure 2. This spring is looped at two opposite sides of the shaft 26, and bears thereagainst. The ends of this spring are fast to the flange 73 by means of screws 79, and the spring is further held in place by a stud 80 also carried by the flange 73.

The Underwood machine is provided with a platen-shifting mechanism for elevating the platen to upper-case position. This mechanism is controlled by a key, not shown, which, upon depression thereof, swings a bell-crank 81 forwardly and elevates a cross-bar or rail 82, which is carried by a pair of shift-frame plates 83 pivotally mounted on a shaft 84. The platen-frame is supported on

said rail 82 by means of a roller 85, which is carried by the platen-frame. In order that the platen-frame may be moved in a vertical plane during the shifting movement thereof, there is provided a pair of links 86 which are pivotally mounted on a cross-shaft 87 and co-operate with pins 88 fast to the platen-frame. In this invention the tally mechanism is carried by the platen-frame and both the supply-spool and the receiving spool are mounted above the platen on the plates 27 and 28 which are slightly inclined toward the rear of the machine. This renders the platen-frame top-heavy and renders shifting thereof to upper-case position somewhat difficult. In order to improve this condition, a pair of equalizing links 89 are pivotally mounted on a cross-bar 90, and are designed to engage pins 91 carried by the platen-frame. Said pins 91 engage the links through a slot or seat 92 in each link in order that the platen may be swung to its displaced position, as shown in Figure 5. Since the links 89 are mounted on brackets 93 carried by the carriage, which does not shift with the platen in this type of machine, it has been found necessary to provide a flexible connection in the form of a spring 94, so that the free ends of the links 89 may move upwardly with the platen when the same is shifted to upper-case position. The links 89 are controlled laterally and in their upward movement by bent ears 89^a forming upon each link an integral part thereof. Said ears straddle the brackets 93, as shown in Figure 3.

The Underwood carriage 20 is slidably mounted on a back rail 96 and a front rail (not shown) in order that the carriage may be letter-spaced. The two rails are carried by the frame 97. The platen-frame is displaceable on the carriage which remains stationary. In order that the platen-frame may be exactly repositioned after being displaced, the platen-frame is provided with locating lugs 98 which rest on the cross-bar 48 carried by the back table 17. Owing to the nature of the tally mechanism carried by the platen-frame, it has been found that in practice the operator usually slams the platen-frame to its normal position, thereby straining the locating mechanism. In order that this delicate part may not be accidentally damaged, due to rough handling of the machine, the rear of the tally mechanism is provided with downwardly-extending supporting arms 100 forming an integral part of the side plates 27 and 28, which arms strike the heavy cross-bar 90 mounted on the carriage.

The machine is provided with the usual line-spacing mechanism, which includes a reciprocating slide (not shown) for rotating a line-spacing wheel 101 during the returning movement of the carriage. The line-spacing wheel is operatively connected by means of a

train of gears 102 and 103 to a gear 104 carried by the platen-shaft.

Referring more particularly to Figure 7, it will be noted that in addition to the regular carbon-carrier 15, there is provided another carbon-carrier 105, which may be of the form disclosed in my said application No. 108,451. This carrier 105 is mounted over the regular carbon-carrier 15 and is spaced therefrom by means of posts 106. The upper web, indicated by the numeral 107, is alternately used with the lower web 13, and, although either web may be operated singly, the two carbon-carriers are simultaneously operated to strip only the carbons in the active web. The two webs may, of course, be either fan-folded or consist of distinct groups of related webs, such a group being understood as either a fan-fold or a group of web-plies.

In order to facilitate the manipulation of the webs when stripping the carbons, there is provided a cross-plate 108 at the delivery side of the platen. This plate serves as a shelf for separating the tally-strip 23 from the web, and is secured to the side plates 27 and 28 by means of rivets 109.

Variations may be resorted to within the scope of the invention, and portions of the improvements may be used without others.

Having thus described my invention, I claim:

1. A tally-mechanism for a web-manifolding typewriting machine having a forwardly-displaceable platen-frame and a platen thereon, said mechanism including a supply-spool and a take-up spool which are both carried by the platen-frame and simultaneously displaceable forwardly therewith, permitting a tally-strip extending from the supply-spool about the platen to the take-up spool to remain upon the platen during displacement of the latter, the tally-strip normally overlying the web and rendering it inaccessible, and means for moving the tally-strip up and off from the web as a unit with the spools, to afford access to the web.

2. In a continuous billing typewriting machine having a platen, a displaceable platen-frame and a carriage supporting said frame and extending to the rear thereof for conducting a fan-folded web to said platen and for guiding interleaved carbons between the plies of the web and also an extra carbon overlying the upper ply of the web, a tally-mechanism displaceable with the platen and including a supply spool at the introductory side of the platen, and a receiving spool at the delivery side of the platen for conducting a tally-strip above the web and carbons and around the platen, said spools and said platen retaining their relative positions to each other upon said platen-frame in normal and displaced positions of the platen, and the spools and tally-strip

swinging upwardly and forwardly clear of the web at the platen-displacing operation.

3. A tally-mechanism for a typewriting machine having a displaceable platen-frame, said mechanism including side plates rigidly carried by the platen-frame in such manner as to be displaceable therewith, a supply spool journaled in said plates, manually-controlled means for locking said spool at will, thereby preventing rotation thereof, a receiving spool for winding a strip therearound and also journaled in the plates, said strip being conducted around the platen from said supply spool, and means for winding said receiving spool in one direction, their being independent means including a ratchet-and-pawl mechanism for preventing back rotation of said receiving spool.

4. A tally-mechanism for a typewriting machine having a displaceable platen-frame, said mechanism including side plates carried by the platen-frame, a supply spool journaled in said plates, manually-controlled means for locking said spool at will, thereby preventing rotation thereof, a receiving spool for winding a strip therearound, said strip being conducted around the platen from said supply spool, manual means for winding said receiving spool in one direction, means including a ratchet-and-pawl mechanism for preventing back rotation of said receiving spool, and manually-operable means for rendering the pawl in said last-mentioned mechanism ineffective, said last-mentioned means including a finger-piece pivotally mounted on one of the plates and a cam carried by said finger-piece, said cam being effective to engage the pawl to thereby move it out of engagement with the ratchet-wheel.

5. In a continuous billing typewriting machine having a platen, a displaceable platen-frame and means for shifting said platen to upper-case position from normal lower-case position, a tally-strip mechanism carried by said platen-frame, said mechanism including side plates rigidly secured to said displaceable platen-frame and a supply-spool journaled in said plates in such manner as to be shiftable together with the platen, and independent means for guiding said platen-frame during shifting movement thereof, there being means to take up said strip beyond the platen.

6. In a continuous billing typewriting machine having a platen, a displaceable platen-frame and means for shifting said platen to upper-case position from normal lower-case position, a tally-strip mechanism rigidly carried by said platen-frame, said mechanism including side plates secured to said displaceable platen-frame and supply and receiving spools journaled in spaced relation in said plates so as to be displaceable and shiftable together with the platen, and means for guid-

ing said platen-frame during shifting movement thereof, including pivotally-mounted links, said links having a slot in each for normally receiving studs carried by the end plates of said platen-frame.

7. In a continuous billing typewriting machine having a displaceable platen-frame, said platen-frame being normally held in its operating position by means of a spring-held latch, said latch being manually releasable prior to swinging the platen-frame, a tally-mechanism carried by said platen-frame and swingable therewith, said mechanism including a supply spool and a receiving spool, a tally-strip being drawn from said supply spool downwardly around the platen and being rewound onto the receiving spool, said receiving spool having a finger-wheel at the end thereof for winding the strip therearound, means for preventing back-rotation of said receiving spool, the supply spool being frictionally held to prevent accidental unwinding of the strip, and normally-ineffective means for automatically locking the supply spool against rotation thereof during displacement of the platen-frame, said last-mentioned means being operatively connected to the platen-frame-locking latch in a manner to operate when the latch is swung to its ineffective position.

8. In a continuous billing typewriting machine having a displaceable platen-frame, said platen-frame being normally held in its operating position by means of a spring-held latch, said latch being manually releasable prior to swinging the platen-frame, a tally-mechanism carried by said platen-frame and swingable therewith, said mechanism including a supply spool and a receiving spool, a tally-strip being drawn from said supply

spool downwardly around the platen and being rewound onto the receiving spool, said receiving spool having a finger-wheel at the end thereof for winding the strip therearound, means for preventing back rotation of said receiving spool, the supply spool being frictionally held to prevent accidental unwinding of the strip, and normally-ineffective means for automatically locking the supply spool against rotation thereof during displacement of the platen-frame, said last-mentioned means including a ratchet-wheel associated with the supply spool, a normally-ineffective pawl for locking said ratchet-wheel, and means for operatively connecting said pawl with the platen-frame-locking latch in a manner to lock said ratchet-wheel upon swinging the latch to ineffective position.

9. In a tally-mechanism having a supply spool, said supply spool being carried by a rotatably-mounted shaft, means for facilitating the manual replacement of the supply spool, said means including a collar fast to the shaft, said collar carrying a driving pin

- engaging a hole in one of the flanges of the supply spool, and means for frictionally holding the other flange of the spool on said shaft, said last-mentioned means being also effective to prevent lateral displacement of the 5 spool on said shaft, said frictional means including a spring resiliently mounted on one of the flanges, said spring bearing on the shaft.
10. In a continuous billing typewriting machine having a displaceable platen supported by a platen-frame including a pair of end plates displaceable therewith, and means for shifting said platen to upper-case position, said platen being normally in lower-case position, studs upon said end plates, and means for guiding said platen during shifting movement thereof, including pivotally-mounted links having an open slot in each 15 for receiving the studs carried by the end plates of said platen, said platen and end plates being swingable to disengage the studs from said slots and permit displacement of said platen.
15. In a continuous billing typewriting machine having a platen and a displaceable platen-frame therefor, a tally-mechanism carried by said platen-frame in such manner as to be displaceable therewith and including both a supply and a rewind spool, said supply spool being frictionally mounted on a supporting shaft, and manually-operable means for locking said shaft against rotation in order to hold the supply-spool stationary 20 while changing webs on the platen in displaced position thereof.
20. In a continuous billing typewriting machine having a platen and a displaceable platen-frame therefor, a tally-mechanism carried by said platen-frame and displaceable therewith, said tally-mechanism including both a supply-spool and a take-up spool, said supply spool being frictionally mounted on a rotatable supporting shaft, manually-operable means for locking the shaft against 25 rotation, and manual means for rotating the take-up spool in one direction to wind the strip about the same, there being means including a ratchet-wheel carried by the take-up spool, and a pawl co-operating with said ratchet-wheel to prevent back rotation of said spool.
25. In a continuous billing typewriting machine having a displaceable platen, and means for conducting a multiple-ply web therearound, and the combination with means for interleaving and shifting carbons between the plies of the web, of a record-sheet-carrying mechanism including a frame displaceable with the platen, a record-sheet supply roll and a record-sheet receiving roll spaced apart on said frame, there being a shaft for said supply roll, positive means for preventing back rotation of the receiving roll, frictional means associated with the supply 30 roll shaft for keeping the record-sheet under tension, and manually-releasable means for positively locking the supply roll to prevent accidental slackening of the record-sheet during the platen-displacing operation. 70
30. In a continuous billing typewriting machine having a displaceable and shiftable platen-frame, means for guiding the movement of the platen-frame during a shifting movement thereof, said means including a pair of resiliently supported links pivotally mounted on a fixed bar at the rear of the platen-frame, and pins carried by the platen-frame for displaceably co-operating with said links to both guide the platen-frame in a vertical plane during a shifting movement and tend to raise the platen-frame to shifted position. 75
35. In a web-manifolding typewriting machine, the combination with a platen, a main carriage, and means on the carriage for presenting to the platen either one of a plurality of composite webs comprising interleaved web-plies and carbons, while the remaining or inactive web is maintained away from the platen, of a platen-frame displaceable upwardly and forwardly for straightening out either composite web preparatory to stripping the carbons, and tally-strip spools carried upon said platen-frame back of the 80 platen and above the active web, with the tally-strip and spools overlying and thereby rendering inaccessible the active web; said spools and tally-strip being movable upwardly and forwardly with the platen-frame to clear the web at the platen-displacing operation, to give access for withdrawing the active web from the platen and substituting the inactive web therefor. 85
40. In a web-manifolding typewriting machine having a rotatable platen, and capable of typing either one of several groups of webs, the combination with a displaceable platen-frame, of means for positioning a continuous record-sheet upon the platen beneath said webs in such manner as to receive a condensed copy of all items which are typed on all of said groups of webs, said means including both a supply-spool and a take-up spool for said record-sheet rotatably mounted in spaced relation to said platen, and also displaceable therewith in such manner as to retain their relation thereto, and means for locking the two spools against rotation thereof during displacement of the platen in order to prevent accidental displacement of the record-sheet in relation to the printing line on the platen while changing the webs on the machine. 90
45. In a typewriting machine having a main carriage, a platen, a displaceable swinging platen-carrier, a shift-frame mounted on said carriage and supporting said platen-carrier, means for shifting the platen, the carrier and the shift-frame to upper-case position. 95
50. In a typewriting machine having a main carriage, a platen, a displaceable swinging platen-carrier, a shift-frame mounted on said carriage and supporting said platen-carrier, means for shifting the platen, the carrier and the shift-frame to upper-case position. 100
55. In a typewriting machine having a main carriage, a platen, a displaceable swinging platen-carrier, a shift-frame mounted on said carriage and supporting said platen-carrier, means for shifting the platen, the carrier and the shift-frame to upper-case position. 105
60. In a typewriting machine having a main carriage, a platen, a displaceable swinging platen-carrier, a shift-frame mounted on said carriage and supporting said platen-carrier, means for shifting the platen, the carrier and the shift-frame to upper-case position. 110
65. In a typewriting machine having a main carriage, a platen, a displaceable swinging platen-carrier, a shift-frame mounted on said carriage and supporting said platen-carrier, means for shifting the platen, the carrier and the shift-frame to upper-case position. 115
70. In a typewriting machine having a main carriage, a platen, a displaceable swinging platen-carrier, a shift-frame mounted on said carriage and supporting said platen-carrier, means for shifting the platen, the carrier and the shift-frame to upper-case position. 120
75. In a typewriting machine having a main carriage, a platen, a displaceable swinging platen-carrier, a shift-frame mounted on said carriage and supporting said platen-carrier, means for shifting the platen, the carrier and the shift-frame to upper-case position. 125
80. In a typewriting machine having a main carriage, a platen, a displaceable swinging platen-carrier, a shift-frame mounted on said carriage and supporting said platen-carrier, means for shifting the platen, the carrier and the shift-frame to upper-case position. 130

tion, said means including a key-controlled mechanism operatively connected with the shift-frame, and a pair of co-operating links at the sides of the platen-frame for guiding said swinging carrier up and down with the shift-frame, said links pivoted at their forward ends to the swinging frame and at their rear ends to the main carriage, the forward pivots being open to permit the upward and forward displacement of the swinging carrier.

18. In a web-manifolding typewriting machine having a rotatable platen, the combination with a platen-frame for said platen, said frame displaceable for carbon-stripping, of a pair of resiliently-supported counterbalancing and guiding members on said machine having open seats to receive said platen-frame in normal position for the double purpose of relieving the shock incidental to restoring said platen and frame and also for guiding the same in shifting movement, there being a tally-mechanism mounted on said platen-frame and also means to shift said frame and tally-mechanism, said open seats permitting the displacement of the platen-frame for the carbon-stripping operation.

19. In a continuous billing typewriting machine having a rotatable platen, the combination with a displaceable platen-frame therefor, of a tally-mechanism including a supply-spool and a take-up spool mounted on said platen-frame in such manner as to be displaceable with the platen, there being a tally-strip extending from said supply-spool about the platen to said take-up spool, and means operable upon displacement of said platen and frame for automatically locking said supply-spool against rotation in order to retain said tally-strip in position upon the platen while changing webs upon the machine, there being also means to simultaneously hold said take-up spool stationary.

20. In a web-manifolding typewriting machine having a rotatable platen, and capable of typing either one of several groups of webs, the combination with a displaceable platen-frame, of means for positioning a continuous record-sheet upon the platen beneath said webs in such manner as to receive a condensed record of all items which are typed on all of said groups of webs, said means including both a supply-spool and a take-up spool for said record-sheet rotatably mounted in spaced relation to said platen and displaceable therewith while retaining their relation thereto, means for locking the supply-spool against rotation thereof during displacement of the platen, and independent means for locking said take-up spool in order to retain said tally-strip in typing position upon the platen while changing said webs.

21. In a continuous billing typewriting machine having a displaceable platen-frame and a platen thereon, the combination with

means for conducting a web to said platen, of a tally-mechanism mounted on said platen-frame in such manner as to be displaceable therewith and having both a tally supply-spool and a receiving spool thereon, there being a tally-strip extending from said supply-spool about the platen to the receiving spool, means to lock both said spools against rotation and prevent slackening of the tally-strip during displacement of the platen in order to retain said tally-strip in position thereon when changing said web, and means to rotate said receiving spool in restored position of the platen to take up said strip from about the same.

22. In a continuous billing typewriting machine having a displaceable platen-frame and a platen thereon, the combination with means for conducting a web to said platen, of a tally-mechanism mounted on said platen-frame in such manner as to be displaceable therewith and having both a tally supply-spool and a receiving spool thereon, there being a tally-strip extending therefrom to the platen and means to take up said strip from the delivery side of the platen, and means to lock said supply-spool during displacement of the platen in order to retain said tally-strip in position thereon when changing said web.

23. In a continuous billing typewriting machine having a displaceable platen-frame and a platen thereon, the combination with means for conducting a web to said platen, of a tally-mechanism mounted on said platen-frame in such manner as to be displaceable therewith and having a tally supply-spool thereon, and a latch which is effective to normally lock said platen-frame in normal operative position and which upon releasing the same in order to permit displacement of the platen is effective to lock said supply-spool against rotation in order to automatically hold said tally-strip upon the platen when displacing the same in order to manipulate said web.

24. In a continuous billing typewriting machine having a displaceable platen-frame and a platen thereon, the combination with means for conducting a web to said platen, of a tally-mechanism mounted on said platen-frame in such manner as to be displaceable therewith and having a tally supply-spool thereon, there being both a tally-strip extending therefrom to the platen and means to take up said strip from the delivery side of the platen, a lock for holding said supply-spool against rotation during displacement of the platen in order to hold said tally-strip in position thereon when said web is changed, and a latch for said platen-frame which is effective to release said supply-spool lock upon restoring the platen and locking the platen-frame and tally-mechanism in normal operative position.

25. In a continuous billing typewriting ma-

chine having a displaceable platen-frame and a platen thereon, the combination with means for conducting a web to said platen, of a tally-mechanism mounted on said platen-frame in such manner as to be displaceable therewith and having a tally supply-spool thereon, there being both a tally-strip extending therefrom to the platen and means to take up said strip from the delivery side of the platen, a lock for holding said supply-spool against rotation during displacement of the platen in order to hold said tally-strip in position thereon when said web is changed, and a finger-piece which is operable to release said supply-spool lock upon restoring the platen to normal position.
